UNITED STATES PATENT OFFICE.

FREDRIC D. OGDEN, OF BAYONNE, NEW JERSEY; J. EDWARD OGDEN, ADMINISTRATOR OF SAID FREDRIC D. OGDEN, DECEASED, ASSIGNOR, BY MESNE ASSIGNMENTS, TO THE PATENT APPLIANCE COMPANY, A CORPORATION OF NEW YORK.

BOLT.

1,065,266.

Specification of Letters Patent. Patented June 17, 1913.

Application filed January 28, 1910. Serial No. 540,485.

To all whom it may concern:

Be it known that I, FREDRIC D. OGDEN, a citizen of the United States of America, and a resident of Bayonne, county of Hudson and State of New Jersey, have invented certain new and useful Improvements in Bolts, of which the following is a specification, reference being had to the accompanying drawings, forming a part thereof.

10 My invention relates to anchor bolts, and particularly to the type of anchor bolt comprising two parts of such form that in one position thereof the head portions may be inserted through a hole of such size that 15 when the parts are readjusted to their final position the head will be prevented from returning through the said hole. This style of bolt is particularly adapted to sheet metal and other work wherein ready access can- 20 not be had to the rear thereof. An example of this is readily found in sheet metal ceiling construction.

25 My invention consists in providing the members of such a bolt with a lateral pro- jection such as will constitute an abutment to rest against the front face of the part to which the bolt is applied, and against the opposite face of which the head portions of the members bear.

30 The objects of my invention are first, to prevent the bolt from accidentally slipping clear through the hole and becoming lost; second, to hold the bolt steady while the nut or other portion for engagement with the 35 stem is being applied thereto, and third, to permanently steady the bolt and lend rigidity thereto in use.

35 My invention also consists in certain novel features of construction such as will 40 be fully pointed out hereinafter, and in order that my invention may be thoroughly understood, I will now proceed to describe certain structures constituting embodiments thereof, having reference to the accompanying drawings illustrating the same, and will 45 then point out the novel features in claims.

In the drawings: Figure 1 is a view in side elevation of an anchor bolt constructed in accordance with my invention, showing

the same as applied in use, the parts en- 50 gaged by the bolt and a nut upon the bolt being shown in vertical transverse section. Fig. 2 is a detached view in side elevation of the bolt and nut, the point of view thereof being at right angles to the point 55 of view of Fig. 1. Fig. 3 is a view partly in plan and partly in horizontal section of the bolt. Fig. 4 is a view of a slightly modified form of bolt. Fig. 5 is a top view of the same. Fig. 6 is a view in side elevation 60 similar to Fig. 1, of a further modification. Figs. 7 and 8 are views in side elevation at right angles to each other, of an eye bolt of the anchor type, and also constituting an embodiment of my invention. 65

The bolt comprises two complementary members conveniently of substantially L-shaped form, each comprising an arm 10 and an arm 11 at an angle thereto. The arms 10 are arranged to lie side by side with 70 each other when the bolt is in use, to form a stem, while the arms 11 are arranged to project laterally in opposite directions to form a head. In the form of bolt shown in Figs. 1 to 6 inclusive the two members are com- 75 posed of material which is substantially semi-circular in contour, the flat sides there- of being against each other, and the ex- terior portions are screw-threaded so that the stem as a whole is adapted for co-en- 80 gagement with a threaded nut 12. The members are inserted through a hole 13 in a structure 14, with which they are to be engaged, by being adjusted to a position with their head portions 11-11 against each 85 other, as is common in this type of bolt, the parts being thereafter readjusted to their final position with the stem portions 10-10 against each other, after the head has been so inserted. The stem portions 10 are pro- 90 vided with lateral projections 15 adjacent the head portions 11 but spaced therefrom a distance preferably equal to about the thickness of the structure 14 with which the bolt is intended to be employed, whereby 95 when the said bolt is employed the adjacent faces of the said lateral projections and the head portions may engage opposite sides of

the said structure. These projections will act to prevent the bolt from passing clear through the hole 13 when being inserted therein, and will tend to hold the two members firmly and in proper relation with respect to each other while the nut 12 is being applied. This will facilitate the application of the nut and will also prevent the possibility of the parts being improperly adjusted when the nut is applied,—that is to say, it will prevent one member being moved longitudinally with respect to the other, such as might readily happen without these projections, under which circumstances but one of the head portions would be in engagement with the structure 14. The presence of these projections also, of course, lend rigidity to the structure, as a whole, in that they tend to steady the parts independently of the nut. The hole 16 in the part 17 to be secured to the structure 14 is, of course, made of a sufficient size to receive these projections 15, as will be well understood. These projections may be conveniently formed by offsetting a portion of the metal of the stem, and three modifications of this are shown in the drawings. In Figs. 1, 2 and 3 the projections are formed by pinching the stem portions at right angles to their surfaces, thereby causing the pinched portions to extend in the direction of the flat surfaces, as will be readily understood by reference to the drawings. In Figs. 4 and 5 a similar effect is formed by an oblique cut 18 in the stem, by which a portion is caused to extend laterally, while in Fig. 6 the entire stem portion is bent outward as is shown at 19. In either case a recess is formed complementary to the part which extends laterally.

In Figs. 7 and 8 I have shown an eye bolt constructed in a similar manner, the two stem portions being provided with ring-like extensions 20 instead of being screw-threaded to receive a nut. In this case the two members are, of course, kept together by some part such as a hook or the like which engages the ring-like portions, the lateral projections 15 acting to steady the device and to prevent the parts from getting out of adjustment.

What I claim is:

1. A fastener comprising two complementary members each comprising a stem portion and a head portion, and provided with a lateral projection upon the stem in proximity to the head portion, but spaced therefrom, whereby the said projection and head portion may engage opposite sides of a structure with which the bolt is to be employed when it is so employed.

2. A bolt comprising two complementary members each comprising a threaded stem portion and a head portion, and provided

with a lateral projection upon the stem in 65 proximity to the head portion, but spaced therefrom, whereby the said projection and head portion may engage opposite sides of a structure with which the bolt is to be employed when it is so employed. 70

3. A fastener comprising two L-shaped members, one arm of each member adapted to lie side by side with the corresponding arm of the other member to constitute a stem, and the other arm adapted to project 75 oppositely to form a head, the first said arms being provided each with a lateral projection in proximity to, but spaced apart from, the arms constituting the head, whereby the said projections and the said head may engage opposite sides of a structure with which the bolt is to be employed when it is so employed. 80

4. A bolt comprising two L-shaped members of semicircular contour in cross section, 85 one arm of each member adapted to lie with its flat side against the flat side of the corresponding arm of the other member, the said arms being screw-threaded on their curved sides whereby they together constitute a screw threaded stem the other arms being arranged to project oppositely to form a head, each of the first said arms being provided with a lateral projection in proximity to but spaced apart from, the arms constituting the head, whereby the said projection and the arms constituting the head may engage opposite sides of a structure with which the bolt is to be employed when it is so employed. 90

5. A fastener comprising two complementary members each comprising a stem portion and a head portion, and provided with a lateral projection upon the stem in proximity to the head portion, but spaced therefrom, whereby the said projection and head portion may engage opposite sides of a structure with which the bolt is to be employed when it is so employed, the stems having recessed portions corresponding to the laterally projecting portions. 95

6. A fastener comprising two complementary members each comprising a stem portion, and a head portion, the stem portion having a part thereof laterally offset in 110 proximity to the head portion, whereby the said lateral offset may engage the side of a structure opposite to that engaged by the head portion when the said bolt is employed in use. 115

7. A fastener comprising two L-shaped members of semicircular contour in cross section, one arm of each member adapted to lie with its flat side against the flat side of the corresponding arm of the other member, the 125 other arms being arranged to project laterally to form a head, a portion of each of the first said arms being bent outward and back

again in proximity to, but spaced apart from, the arms constituting the head, to constitute an abutment.

8. A fastener comprising two rings having flat opposed faces, each having a projecting stop arm and a longer arm turned at an angle out of the plane of the stop arms, the

angular arms of the two members being turned in opposite directions.
